UNITED STATES PATENT OFFICE.

CLARENCE DUNAWAY, OF MILFORD, MASSACHUSETTS, ASSIGNOR TO HOPEDALE MANUFACTURING COMPANY, OF MILFORD, MASSACHUSETTS, A CORPORATION OF MASSACHUSETTS.

PROTECTOR MECHANISM FOR LOOMS.

Application filed December 8, 1923. Serial No. 679,351.

The present invention relates to protector mechanisms for looms and more particularly to the construction of a frog for use in protector mechanisms.

5 The object of the present invention is to provide a frog which will hold its steel in proper position even when subject to heavy vibration. To this end the invention consists in the frog hereinafter described and 10 particularly defined in the claims.

In the accompanying drawings illustrating the preferred form of the invention Fig. 1 is a plan view of the improved frog; Fig. 2 is an elevation, partly in section, of the 15 frog; and Fig. 3 is a section on line 3—3 of Fig. 2.

The illustrated embodiment of the invention comprises a frog having a top plate 4 and a bottom plate 6 adapted to slide upon a 20 projection 8 on the side frame of the loom. The frog is also provided with forwardly extended side plates 10 adapted to be positioned under a pair of lugs 12 upon the loom frame. The rear end of the frog is retained 25 in position by a hold-down 14 secured to the frame and having a forwardly extended lug 16 held down firmly in engagement with the top plate 4 of the frog. According to the usual construction, the bottom plate 6 of the 30 frog is adapted to slide under the projection 8 of the loom frame when the frog is moved forwardly. The frog may be connected through a link 18 with the whip roll to move the latter forward and slacken the warps to 35 prevent a smash. It will be seen that the forward end of the frog is always maintained beneath the lugs 12, whereas the rear end is always held down either by the engagement of the bottom plate 6 under the projection 8 or by the engagement of the 40 lug 16 and the top plate 4.

The top plate 4 is provided with an opening of the usual form in which the frog steel 20 is received, the latter being adapted 45 to be struck by the dagger of the protector mechanism in the usual manner whenever a shuttle absence from both boxes on the forward beat of the lay is indicated. The side plates 10 have upwardly inclined projections 50 formed with recesses 24 into which the steel may be inserted from the rear in the usual manner. After insertion of the steel a pair of pins 26 are driven into suitable holes in the top plate and then bent over, as 55 indicated in Fig. 2, to hold the steel in place.

The steel is further held by a spring 28 secured under a screw 30 and having its rearward end curved and pressing upon the top of the steel. This forms a yielding connection to hold the steel normally in its proper position against vibrations of the loom, at the same time allowing the steel to move slightly when it has been engaged by the dagger upon a proper indication of shuttle absence.

While it is preferred to employ the specific construction and arrangement of parts shown and described, it will be understood that this construction and arrangement is not essential except so far as specified in the 70 claims and may be changed or modified without departing from the broader features of the invention.

The invention having been described, what is claimed is:—

1. A protector mechanism for looms comprising a frog having an opening to receive the frog steel, a frog steel adapted to be received in the opening in the frog, and a spring carried by the frog having a portion bearing on the steel resiliently to hold it in place.

2. A protector mechanism for looms comprising a frog having an opening to receive the frog steel, a frog steel adapted to be received in the opening in the frog, and a pin carried by the frog having a portion bearing against the steel to hold it in the opening.

3. A protector mechanism for looms comprising a frog having an opening to receive the frog steel, a frog steel adapted to be received in the opening in the frog, and a pair of pins, one at each end of the steel, carried by the frog and bearing on the steel to hold it in the opening.

4. A protector mechanism for looms comprising a frog having an opening to receive the frog steel, a frog steel adapted to be received in the opening in the frog, a pin carried by the frog having a portion engaging the steel to prevent its displacement from the opening, and a spring secured to the frog having a portion bearing on the steel to hold it in place.

5. A protector mechanism for looms comprising a frog, a frog steel, and a yielding device for holding the frog steel in position on the frog.

CLARENCE DUNAWAY.
